DESIGN.

J. A. READ.
FIRE PLACE LINING.

No. 19,439.

Patented Nov. 19, 1889

UNITED STATES PATENT OFFICE.

JOSEPH A. READ, OF PHILADELPHIA, PENNSYLVANIA, ASSIGNOR TO GILBERT COMBS, JOHN BAWDEN, AND JOHN H. BAWDEN, OF SAME PLACE.

DESIGN FOR A FIRE-PLACE LINING.

SPECIFICATION forming part of Design No. 19,439, dated November 19, 1889.

Application filed January 9, 1889. Serial No. 295,880. Term of patent 7 years.

To all whom it may concern:

Be it known that I, JOSEPH A. READ, a citizen of the United States, residing in Philadelphia, Pennsylvania, have invented or produced a new and original Design for a Fire-Place Lining, of which the following is a specification.

My design for a fire-place lining is fully shown in the accompanying photograph.

10 The general character of the design is the conventionalized representations of scrolls, leaves, and flowers.

15 The design comprises both the back and side plates of the fire-place. The back plate A has a central urn a, mounted upon a transverse scroll b, under which is the representation of lattice-work, the urn containing conventionalized representations of leaves, flowers, and sprays or garlands. At the base of 20 the urn are representations of flowers and leaves, and directly below the urn are a series of scrolls c, branching from a central point at the base of the back plate. On each side of the back plate are vertical bars d, terminating at their upper ends in a series of scrolls 25 and bordered on their outer sides by representations of leaves and flowers, and filling the space between the urn and these vertical

bars are representations of large leaves. The ornamentation of the side panels B comprises 30 the side bars d' with their floral ornaments, the transverse scroll b', and base-scroll c', but another scroll replaces the urn of the back plate, the lattice-work is dispensed with, and the minor floral ornamentation is somewhat 35 modified.

I claim—

1. In a design for a fire-place lining, the design for the back plate, comprising an urn, scrolls, and bars, and conventionalized leaves, 40 flowers, sprays, and garlands, arranged substantially as described, and shown in the annexed photographic illustration.

2. In a design for a fire-place lining, the design for the side plates, comprising the bars, 45 floral ornaments, and scrolls, arranged substantially as described, and shown in the annexed photographic illustration.

In testimony whereof I have signed my name to this specification in the presence of two 50 subscribing witnesses.

JOSEPH A. READ.

Witnesses:

WILLIAM D. CONNER,
HARRY SMITH.
